Primary Examiner — Rashida Johnson(74) *Attorney, Agent, or Firm* — Fredrikson & Byron, P.A.(57) **CLAIM**

I claim the ornamental design for the coat, as shown and described.

DESCRIPTION

FIG. 1 is a front view of the coat showing my new design; the coat shown completely closed;

FIG. 2 is another front view thereof; showing the coat partially opened with the collar folded down;

FIG. 3 is another front view thereof; left side of the coat shown completely unbuttoned and unzipped;

FIG. 4 is another front view thereof; showing the first layer of the front opening completely unbuttoned, unzipped and folded back, a second layer of the front opening shown zipped; and,

FIG. 5 is a rear view thereof.

The broken lines in FIGS. 1-5 represent stitching.
